UNITED STATES PATENT OFFICE.

HARRY C. LEE, OF RIDGEWOOD, NEW JERSEY, ASSIGNOR, BY MESNE ASSIGNMENTS, TO THE KEMPSHALL MANUFACTURING COMPANY, OF NEW YORK, N. Y., A CORPORATION OF NEW JERSEY.

GOLF-BALL.

No. 895,476.

Specification of Letters Patent. Patented Aug. 11, 1908.

Application filed August 11, 1902. Serial No. 119,198.

To all whom it may concern:

Be it known that I, HARRY C. LEE, a subject of the King of Great Britain and Ireland, residing in Ridgewood, in the county of Bergen and State of New Jersey, have invented certain new and useful Improvements in Golf-Balls, of which the following is a specification.

This invention relates to golf balls, and 10 its object is to produce at low cost a ball having excellent flying qualities and not unduly sensitive to a light blow.

In the drawings forming part of this specification, Figure 1 is a view, partly in section, 15 of a ball made in accordance with my invention. Fig. 2 is a view of the preferred form of centerpiece. Fig. 3 shows the Fig. 2 device overwound with twine. Fig. 4 shows the Fig. 3 device after the application of 20 gutta-percha thereto; Fig. 5 is an enlarged sectional segment of the ball. Fig. 6 shows a length of helical wire spring used in forming the centerpiece of the ball.

In the several views, similar parts are 25 designated by similar characters of reference.

I coil or wind up in miscellaneous directions a length of helical wire spring 1, preferably steel, to form a centerpiece A, which is highly resilient. This centerpiece I bind 30 with numerous windings of coarse twine 2 or other tough material, preferably fibrous, but softer than the wire 1, forming a ball B, Fig. 3. The numerous large and small interstices in the outer portion of the latter I 35 fill with plastic material 3, such as gutta-percha, making a ball C. The gutta-percha may be applied by dipping the ball into a solution of the material, or gutta-percha may be heated and forced or otherwise 40 worked into the meshes of the windings 2. Upon the filling C I apply a wear-resisting cover D of gutta-percha thus completing the golf ball. The gutta-percha of the cover 45 unites to the gutta-percha filling 3 of the twine ball, so that the strength of the cover is increased. If desired, sufficient gutta-percha may be applied upon the windings of twine 2 to form the shell D, which may thereafter be shaped it, a press.

50 The windings of twine 2 preferably bind tightly upon the centerpiece A, and it will be seen that the mass of springs under such confinement becomes a material factor in con-

tributing to the flight of the ball under a heavy blow; while owing to the presence of 55 the windings of twine 2 the ball is inactive under a light blow, and more so because of the presence of the gutta-percha 3 throughout said windings, especially since this portion of gutta-percha is effectually united to 60 the outer gutta-percha cover or shell D.

It will be seen that the ball comprises an open-work or cellular spring central structure A, overwound with material which by preference is substantially unyielding in longitudinal direction; that the hard filling or core illustrated at Fig. 3 is treated with plastic material 3, to which the cover D adheres or joins, said material 3 having an affinity for the material of said cover. 70

Variations may be resorted to within the scope of my improvements.

Having described my invention, I claim—

1. A playing ball comprising windings of helical wire spring, and a cover of wear-resisting material. 75

2. A playing ball comprising windings of helical wire spring, and a cover of gutta-percha.

3. A playing ball comprising a sphere of 80 helical wire springs wound in miscellaneous directions, binding material upon said sphere, and a gutta-percha cover.

4. A playing ball comprising a sphere of 85 helical wire springs wound in miscellaneous directions, binding material upon said sphere, gutta-percha filling the interstices in said windings, and a gutta-percha cover.

5. A playing ball comprising a helical wire spring wound upon itself and bound with 90 twine and gutta percha filling the interstices in said windings, and a gutta percha cover.

6. A playing ball comprising a springy 95 centerpiece of metal, windings thereon of binding material, and a shell of gutta-percha.

7. A playing ball comprising a sphere of 100 helical wire springs wound in miscellaneous directions, binding material upon said springs, and a cover of plastic material mounted thereon.

HARRY C. LEE.
